UNITED STATES PATENT OFFICE.

ALLEN E. HOWE, OF SEATTLE, WASHINGTON.

DESIGN FOR A HOLDER FOR MAGAZINES OR SIMILAR ARTICLES.

Application filed January 18, 1928. Serial No. 24,910. Term of patent 3½ years.

To all whom it may concern:

Be it known that I, ALLEN E. HOWE, a citizen of the United States, residing at Seattle, in the county of King and State of Washington, have invented a new, original, and ornamental Design for a Holder for Magazines or Similar Articles, of which the following is a specification, reference being had to the accompanying drawing, forming part thereof.

Figure 1 is a perspective view, and Fig. 2 is an end elevation of a holder for magazines or similar articles, showing my new design.

I claim:

The ornamental design for a holder for magazines or similar articles, as shown.

ALLEN E. HOWE.
